ATTORNEYS

UNITED STATES PATENT OFFICE.

ELVIN MANN HARTLETT, OF CHICAGO, ILLINOIS.

HOLDER FOR STETHOSCOPES.

Application filed December 29, 1923. Serial No. 683,489.

To all whom it may concern:

Be it known that I, ELVIN MANN HARTLETT, a citizen of the United States, and a resident of Chicago, in the county of Cook and State of Illinois, have invented a new and useful Improvement in Holders for Stethoscopes, of which the following is a full, clear, and exact description.

My invention relates to improvements in holder for stethoscope, and it consists in the combinations, constructions, and arrangements herein described and claimed.

An object of my invention is to provide a holder for a stethoscope that is adapted to rigidly secure a stethoscope to the head of the operator, whereby the operator does not have to hold the stethoscope with his hands.

A further object of my invention is to provide a device of the type described in which the bell of the stethoscope does not have to be grasped by the operator, thereby obviating the necessity of sterilizing the bell every time the stethoscope is used.

A further object of my invention is to provide a device of the type described in which the device for holding the stethoscope, clamps it securely to the head of the operator whereby the bone structure of the head acts as a sound conductor and increases the sound from the stethoscope.

A further object of my invention is to provide a device of the type described which is simple in construction and consists of few parts.

Other objects and advantages will appear in the following specification, and the novel features of the invention will be particularly pointed out in the appended claims.

My invention is illustrated in the accompanying drawings forming part of this application, in which

Figure 1 is a side elevation of the device,

Figure 2 is a plan view of the device,

Figure 3 is a front elevation of the clamp,

and

Figure 4 is a plan view of one of the jaws of the clamp.

In carrying out my invention, I provide a clamp carrying support 1 that is adapted to be secured to the head of the operator by means of a band 2. A plate 3 is carried by the support 1 and in turn carries the clamp 4. As clearly shown in Figure 2, the clamp 4 is received in a recess 5 of the plate 3.

The jaws 6 and 7 of the clamp are fash-

ioned so as to grip the stem 8 of the stethoscope at a point where the stem branches into two portions 9 and 10, (see Figure 2). The portions 9 and 10 are in communication with the tubes 11 and 12. In Figure 4 I have shown the shape of the jaw 7. The shape of the jaw 7 is identical with the shape of the jaw 6. It will be noted from this figure that the jaw 7 is hollowed out at 13 so as to receive the pipe 8. In Figure 3 I have clearly shown the hollow or groove 13. The upper jaw 6 is secured to the jaw 7 by means of a wing screw 14. The screw 14 is disposed in an opening 15 in the jaw 6 and in a threaded opening 16 in the jaw 7. When the wing screw 14 is tightened, the jaws 6 and 7 are swung together so as to grip the pipe or stem portion 8.

From the foregoing description of the various parts of the device, the operation thereof may be readily understood. The clamp supporting member 1 is provided with a padding 17 that bears against the head of the operator when the device is worn. When using the stethoscope the pipe 8 is inserted between the jaws 6 and 7 as clearly shown in Figure 1, and is clamped in place by means of the wing screw 14. The ends of the tubes 11 and 12 are inserted in the ears of the operator, and the device is now ready to be used by the operator. As heretofore stated, the bell 18 is rigidly held in place by the clamp 4 and the operator can move the bell to any location desired. The doctor or other person using the device may be using his hands for other purposes while testing the patient. Furthermore, the clamp 4 obviates the necessity of the doctor's holding the bell 18 to the patient with his hand. The bell therefore does not have to be sterilized as is the case when the clamp 4 is not used.

The device is extremely simple in construction, and provides a novel means for securing the stethoscope to the head of the operator. One of the important features of the invention is that the bell 18 is rigidly held, whereby the doctor can move the bell to any desired position by merely moving his head. Another advantage of the device lies in the fact that the jaws 6 and 7 can be readily released to permit the stethoscope to be removed.

The fact that the stethoscope is rigidly clamped to the head of the operator causes

part of the sound waves to travel through the wall of the device itself and by conduction be transmitted to the bone structure of the head, whereby the sound from the stethoscope is increased. If it is desired to further increase the sound, the padding 17 may be removed and the plate 1 clamped directly to the forehead. A direct metal connection is now afforded between the patient being 10 tested and the head of the operator. It will therefore appear that the device performs a double function, i. e., it rigidly supports the bell of the stethoscope and also acts as a sound conductor to the bone structure of the 15 head.

I claim:

1. A holder for a stethoscope comprising a plate, means for securing said plate to the head of a person, a clamp rigidly secured to 20 said plate, said clamp having two jaws, means for moving said jaws into locking engagement with the bell of the stethoscope, the gripping surfaces of said jaws being fash-

ioned so as to conform to the outer surface of the bell.

2. A holder for a stethoscope comprising a head band, a plate carried by said band, a jaw having its shank rigidly secured to said plate, a second jaw, means for moving said jaws toward each other to grip the bell 30 of a stethoscope therebetween, and the gripping surfaces of said jaws being fashioned so as to conform to the contour of the outer surface of the bell.

3. A holder for a stethoscope comprising a head band and a clamp rigidly secured to said head band, said clamp being provided with means for rigidly holding the bell of the stethoscope.

4. A holder for a stethoscope comprising a head band, a plate fastened to said band, and a clamp rigidly secured to said plate, said clamp being provided with means for gripping the bell of the stethoscope so as to cause the bell and band to move as a unit.

ELVIN MANN HARTLETT.
